Geo. F. Melt

UNITED STATES PATENT OFFICE.

MAX REISNER, OF CONEY ISLAND, NEW YORK.

CUTTER-CHUCK.

1,274,598.

Specification of Letters Patent.

Patented Aug. 6, 1918.

Application filed August 16, 1917. Serial No. 186,435.

To all whom it may concern:

Be it known that I, MAX REISNER, a citizen of the United States, and a resident of Coney Island, county of Kings, and State 5 of New York, have invented certain new and useful Improvements in Cutter-Chucks, of which the following is a specification.

My invention is designed more particularly for use in connection with diamond 10 and other cutting "stones" employed in shaping, dressing, and truing up grind stones, and for similar purposes. Such cutting stones vary in size and are more or less irregular in configuration, and the main object of my invention is to afford ample and positive support for such cutter stones during use, the invention consisting in the specific construction and arrangement of parts described and claimed,—distinctive features 15 being a plurality of clamping jaws provided with independent tightening screws to compensate for irregularity of shape of the cutter stones, and in the provision of an axial adjustable rest pin for the support of the 20 cutter stone held between said clamping jaws, all as hereinafter more fully set forth.

In the accompanying drawings,

Figure 1, is a front end view of my improved cutter chuck;

Fig. 2, is a side elevation thereof;

Fig. 3, is a section taken upon plane of line 3—3, Fig. 2;

Fig. 4, is a central longitudinal sectional elevation;

Fig. 5, is a front end view of the jaw piece;

Fig. 6, is a side elevation thereof;

Fig. 7, is a rear end view thereof;

Fig. 8, is a side view of the rest pin;

Fig. 9, is an end view thereof;

Fig. 10, is a side view of the back rest screw;

Fig. 11, is an end view thereof.

c, represents a black diamond or other 45 relatively hard "stone" or cutting medium. As before intimated the natural stones are irregular in size and shape. Hence each of the clamping jaws *j*, is provided with its own set or binding screw *b*. The plural 50 number of clamping jaws *j*, are provided, preferably not less than three,—four being

shown in the drawings as forming a part of the jaw piece *J*, and corresponding binding screws *b*, being positioned in the forward end of the sleeve piece *S*.

The jaw piece *j*, is tapped axially, and its rear portion is formed with a female screw thread *j'*, with which the male-threaded back rest *r*, engages. This back rest *r*, is nicked at its rear end or otherwise formed to facilitate its being turned in the jaw piece *J*, to contact with the inner end of the rest pin *p*, and hold the outer end of the latter firmly and positively against the inner end 55 of the cutter stone *c*.

The inner end of the handle *H*, is formed with a threaded stud *h*, which screws into the rear end of the jaw piece as shown in Fig. 4, which also shows the inner end of the sleeve *S*, overlapping the joint between 60 the handle *H*, and the jaw piece *J*.

Obviously the individual binding screws *b*, afford means whereby each jaw *j*, can be independently adjusted to conform to and contact firmly with the opposed surface of 75 the cutting stone *c*, thereby compensating for unevenness or irregularity in the shape of the latter; and the rest pin *p*, effectually reinforces and sustains the said stone *c*, axially, so that it is held rigidly to its work. 80 Furthermore the back rest screw *r*, provides means for compensating for the wear on the stone *c*, so that practically the whole of the latter may be used before it is necessary to discard the stone and replace it with another, and as such cutting stones are quite expensive the economy thus effected is an 85 important practical advantage.

My device is adapted for drilling, writing and marking; also for making grooves 90 in grinding stones, emery wheels etc., and has general application in the arts where so called refractory stones are used.

What I claim as my invention and desire 95 to secure by Letters Patent is,

A chuck for cutting stones of the character designated, comprising a tubular jaw piece internally threaded throughout the greater portion of its length and having its outer portion formed into a plurality of 100 jaws adapted to clamp a cutting stone, a rest pin in said tubular jaw piece for the

support of the cutting stone, a rest screw abutting against the inner end of said rest pin and engaging with the internal thread in the tubular jaw piece, a handle formed with a threaded stud engaging the internal thread in the said tubular jaw piece, a sleeve overlapping the main portion of the said tubular jaw piece, and radially arranged

5

binding screws in said sleeve, one for each of the clamping jaws of the said tubular 10 jaw piece, for the purpose described.

MAX REISNER.
